United States Patent Office.

JOHN H. ELWARD, OF POLO, ILLINOIS.

Letters Patent No. 96,408, dated November 2, 1869; antedated October 22, 1869.

IMPROVED LIFTING-JACK.

The Schedule referred to in these Letters Patent and making part of the same.

To whom it may concern:

Be it known that I, JOHN H. ELWARD, of Polo, in the county of Ogle, and State of Illinois, have invented a new and useful Improvement in Lifting-Jacks; and I do hereby declare that the following is a full, clear, and exact description thereof, reference being had to the accompanying drawings, and to the letters of reference marked thereon.

Figure 1 is a side elevation of my invention.

Figure 2 is a back view of fig. 1.

Figure 3 is a plan view.

Figure 4 is a horizontal sectional view on line xx of fig. 1.

Similar letters of reference indicate like parts in each of the drawings.

This invention relates to lifting-jacks, and consists, first, in the union of a standard having a concave serrated surface, with a convex serrated reciprocating adjustable lifting-bar, having a lever fulcrumed upon its upper end, and a shifting diagonal supporting-link, the link being suspended from a notch in the front of the standard, and engaging with one of the recesses, in the back of the reciprocating bar.

Second, in the combination of the slips and hooks with the jack, in the manner hereinafter described.

A is a standard, having a concave serrated surface, which registers with the convex reciprocating-bar B.

This standard A has a notch upon its upper front, from which is suspended the shifting diagonal link d.

B is a convex reciprocating bar, supported at any given point by means of the link d, resting in one of the recesses in its back front.

C is a lever, fulcrumed in the upper end of the bar B by means of the pivot e.

b b' are hooks attached to the bar B upon each side of the lever C, upon which the jack can be hung when desired.

The jack may at times become useful as a step. For this purpose, steps made of metal, or other suitable material, are attached to the standard A', in the manner clearly shown in the drawings.

To operate this jack, it is placed under the weight to be raised. The lifting-bar B is then adjusted until the point of its lever C rests immediately under the object. The lever is then depressed, which causes the serrated faces of the standard A and bar B, to become the more firmly locked.

What I claim as my invention, and desire to secure by Letters Patent, is—

1. The standard A, having a concave serrated surface, in combination with the reciprocating adjustable lifting-bar B, having a convex serrated surface, and the shifting diagonal supporting-link d, substantially as shown and described.

2. The combination of the slips g g' with the standard A, and of the hooks b b', with the reciprocating bar B, in the manner shown and described.

In testimony whereof, I hereby sign my name to this specification, in the presence of two subscribing witnesses.

JOHN H. ELWARD. [L. s.]
